UNITED STATES PATENT OFFICE.

WILLIAM C. LEHMAN, OF CANNELTON, INDIANA.

DESIGN FOR A ROUNDABOUT.

60,191.

Specification for Design.

Patented Jan. 10, 1922.

Application filed July 6, 1921. Serial No. 482,855. Term of patent 7 years.

To all whom it may concern:

Be it known that I, WILLIAM C. LEHMAN, a citizen of the United States, residing at Cannelton, in the county of Perry and State of Indiana, have invented a new, original, and ornamental Design for Roundabouts, of which the following is a specification, reference being had to the accompanying drawing, forming part thereof, in which—

Fig. 1 is a top plan view;

Fig. 2 is a side elevation; and Fig. 3 is an end elevation; showing my new design.

I claim:—

The ornamental design for a roundabout, as shown.

In testimony whereof, I, affix my signature.

WILLIAM C. LEHMAN.
